[57] CLAIM

The ornamental design for a handle for a folding blade knife, as shown and described.

DESCRIPTION

FIG. 1 is a front elevational view of a handle for a folding blade knife, showing my new design;

FIG. 2 is a top plan view thereof;

FIG. 3 is a bottom plan view thereof;

FIG. 4 is a right side elevational view thereof; and,

FIG. 5 is a left side elevational view thereof.

The broken line showing of the blade in FIGS. 1, 4 and 5 is for illustrative purposes only and forms no part of the claimed design.

FIG. 1.

FIG. 4.

FIG. 2.

FIG. 5.

FIG. 3.
